UNITED STATES PATENT OFFICE

ALEX TAUB, OF DETROIT, MICHIGAN, ASSIGNOR TO GENERAL MOTORS CORPORATION, OF DETROIT, MICHIGAN, A CORPORATION OF DELAWARE

CYLINDER-HEAD COMBUSTION CHAMBER

Application filed September 21, 1927. Serial No. 221,073.

This invention relates to the combustion chambers of internal combustion reciprocating engines and is particularly applicable to engines in which the combustion space communicating with each cylinder bore lies wholly or approximately within a space that would be bounded by an extension of the internal surface of the cylinder bore; it is particularly applicable to engines of the so-called 10 over-head valve type.

Harshness or smoothness of an internal combustion engine depends upon the rate of pressure rise in the combustion chamber during a combustion period, and detonation depends upon the temperature of the unburned 15 portion of the burning gas. It has been ascertained that rate of pressure rise and temperature of the last gas to burn during a combustion period can be controlled to a considerable extent by combustion chamber form and the relative location of the point of ignition in the chamber in engines of L-head type, wherein a considerable volume of the combustion chamber is off-set laterally from the 20 cylinder bore in order to provide room for valves at one side of the cylinder.

It is an object of this invention to apply to over-head valve or other engines having the combustion space over the piston, the 25 principles found effective in controlling rate of pressure rise and detonation producing temperatures in L-head engines.

The invention comprises a cylinder having a combustion chamber not offset materially 30 from the cylinder bore, of contour and proportions calculated to reduce the maximum rate of pressure rise toward the end of the burning period, and to conduct heat away from that portion of the charge that is last to burn so rapidly as to keep it below the 35 temperature at which it detonates.

In the accompanying drawings in which like reference characters indicate like parts throughout the several views:

Fig. 1 is a cross section through an engine cylinder embodying this invention;

Fig. 2 is a plan view of a head casting belonging to a cylinder block shown in section in Fig. 1, a portion of the casting being shown

in section on a plane normal to the cylinder axes as indicated by the line 2—2 of Fig. 3;

Fig. 3 is an elevation of a portion of a head casting of the form shown in Fig. 2, a part being shown in section on a plane including the cylinder axes, as indicated by the line 3—3 of Fig. 2, and

Fig. 4 is a view of the underside of a fragment of the head casting shown in the other views.

The particular engine illustrated in the drawing is a four-cylinder engine having the cylinder bores arranged upright in line or in tandem relation. The combustion chamber illustrated is, of course, applicable to reciprocating internal combustion engines, whatever may be the position of the cylinder bore axes with respect to a horizontal plane. Therefore, in referring to the combustion chamber and valves, as being above and over 70 the piston or cylinder bore, it is meant that they are opposed to the working face of the piston in whatever angular position the cylinders may be disposed and are confined approximately within a space bounded by the 75 extension of the wall of the cylinder bore beyond the working face of the piston.

In the drawing, 10 indicates a cylinder block; 11 a head casting; 12 a piston adapted to reciprocate in cylinder bore 13; 17 the combustion chamber over the piston; 14 the usual cam shaft; 15 one of the valve push rods operated by the cams on the cam shaft; 16 one of the rocker arms for unseating the valves; 18 one of the poppet valves (in this case an intake valve) for controlling a port of communication between the chamber and a manifold (not shown); 19 a stem attached to said valve and pressed upon by said rocker arm to open the valve and 20 a coil spring such as is generally used for closing the valve. The drawing shows a four-cylinder engine in which adjacent cylinders communicate with a common intake pocket as is indicated at 21. Each exhaust valve port 95 communicates by a single passage 22 with an exhaust manifold (not shown).

The combustion chamber 17 is disposed substantially over or above the working surface of the piston 12. Although shown in the il-

lustrated embodiment as of somewhat great cross sectional area than the cylinder bore, or over-hanging it, the overhang is slight and is not such as to substantially widen the head or cylinder block as compared with what is customary in the over-head valve type of engine. The presence or absence of overhang as shown is not material to the invention and depends mainly on the compression and extent of valve movement required. The combustion chamber 17 comprises a thin space at 23 where the area of wall surface to volume is relatively large shortly after the instant of firing when the piston is at or near the end 10 of its compression stroke. At the opposite side of the chamber 17 from the thin space 23 there is a firing or ignition bay 24, off-set from the chamber as shown in an upward direction. Tapped into this off-set portion or firing bay 24 is a spark plug 25, the ignition points being therefore at considerable distance from the space 23. In the form shown, flame travel, which is progressive from the point of ignition, has to proceed around the 15 corner 24 formed by the boundary wall of bay 24 and the main portion of the chamber 17. By the time the flame front reaches the distant (with reference to the ignition point) side of the chamber containing the thin space 20 23, there will be no unburned gas excepting that in front of the flame in the space 23 and that lying along the reentrant wall 26 which divides the layer of unburned gas in contact with it and causes the gas to flow laterally in 25 opposite directions so that the unburned gas is smoothly deflected, gives up heat to the reentrant wall, and flows without eddying into the relatively thin space 23. Thus the last of the gas to be burned will have heat extracted from it by the large cooling surface in 30 contact with it as compared with the volume. The temperature of the last gas to burn will, therefore, be kept below the temperature at which it detonates under compressions considerably higher than is customary in automobile engines.

As indicated at 27 the roof of the combustion chamber immediately in front of (as regards direction of flame travel) reentrant 35 wall 26 is somewhat higher than it is anywhere else excepting in the ignition bay 24, so that the rate of pressure rise of the unburned gas in front of the flame may be reduced as the flame front approaches the reentrant wall, and crowds unburnt gas before it in opposite directions along said wall and into the space 23.

The form of combustion chamber illustrated and described enables the same results 40 to be obtained in an over-head valve engine as have been obtained in L-head engines as regards smoothness of operation and absence of detonation. By inspection of Fig. 1, it may be imagined that the typical combustion chamber of an L-head engine has been bent at an

angle of 90 degrees, the valve ports having been shifted from the underside of the over-hanging portion to a position in the roof of the chamber where the valves of over-head valve engines are usually placed. The usual over-head valve type of engine has the combustion chamber so compact that it is difficult to locate the point of ignition in such a position that the rate of pressure rise can be slow enough to prevent that harshness which occurs when the charge burns too quickly. By reducing the space between the working face of the piston and the roof of the chamber when the piston is at the end of its compression stroke while, of course, leaving ample room for the valves to open to their full capacity; providing the small volume to surface space 23, and, distant therefrom, the ignition bay 24; an over-head valve engine may be constructed which will be substantially free from detonation and harshness, even though using compressions considerably higher than the normal compressions in gasoline automobile engines of today.

I claim:

1. An engine cylinder having a combustion chamber provided with a portion having intake and exhaust ports disposed in its roof over the cylinder bore, an ignition bay offset upward from the ported portion at one side of the axis of the cylinder bore, and a thin cooling space opposite the ignition bay at the other side of the axis of the cylinder bore, said cooling space having a large ratio of wall surface to included volume, relative to the other portions of the chamber, for the purpose of maintaining the last unburned portion of the burning gas below the temperature at which detonation takes place.

2. An engine cylinder as defined in claim 1 in which the thin cooling space lies between the top of the piston and the roof of the chamber when the piston is at the end of its compression stroke.

3. An engine cylinder having a combustion chamber provided with a portion having intake and exhaust ports disposed in its roof over the cylinder bore, an ignition bay offset upwards from the ported portion at one side of the axis of the cylinder bore and a thin cooling space opposite the ignition bay at the other side of the axis of the cylinder bore, the side wall of the ported portion of the chamber adjacent the entrance to the cooling space having a reentrant surface facing the ignition bay.

4. An engine cylinder as defined in claim 3 in which the height of the ported portion of the chamber increases adjacent the re-entrant side wall whereby to afford an increased expansion space for the gases being forced toward the cooling space by the moving flame front.

5. An engine cylinder having a combustion chamber provided with intake and ex-

haust ports in the roof over the cylinder bore, an ignition bay offset upward from the ported portion at one side of the axis of the cylinder bore and a thin cooling space opposite the ignition bay at the other side of said axis; said cooling space having a large ratio of wall surface to included volume relative to the other portions of the chamber and said ported portion increasing in volume adjacent to the entrance to the cooling space.

6. An engine cylinder having a combustion chamber comprising a portion of relatively great depth and small ratio of wall surface to included volume and a cooling space connecting therewith of relatively small depth and large ratio of wall space to included volume; said portion of relatively great depth having intake and exhaust ports communicating therewith; a sparking device in said portion of relatively great depth disposed adjacent the side opposite the cooling space, said portion of relatively great depth increasing in volume adjacent to the communication between it and said cooling space.

25 In testimony whereof I affix my signature.

ALEX TAUB.
